DESIGN FOR A TOY

Walter S. Carr, Oakwood, Ohio

Application October 8, 1934, Serial No. 53,524

Term of patent 7 years

To all whom it may concern:

Be it known that I, Walter S. Carr, a citizen of the United States residing at Oakwood, in the county of Montgomery and State of Ohio, have invented a new, original, and ornamental Design for Toys, of which the following is a specification, reference being had to the accompanying drawing, forming a part thereof.

Fig. 1 is a front elevation of a toy showing my new design; and Fig. 2 is an end elevation of the same.

I claim:
The ornamental design for a toy, as shown.

WALTER S. CARR.
